FLORAL MEMORIAL MARKER

Montgomery J. Shoemaker, Olean, N.Y.

Application February 18, 1959, Serial No. 54,659

Term of patent 14 years

(Cl. D79—2)

Fig. 3.

Fig. 4.

Fig. 1 is a top plan view of a floral memorial marker, showing my new design;

Fig. 2 is a front elevational view thereof, the legs on the right side of the view being broken off for convenience of illustration;

Fig. 3 is a rear elevational view thereof; and

Fig. 4 is a left elevational view thereof.

The side not illustrated is substantially identical to that shown in the drawing.

This application is a continuation-in-part of my pending application Serial No. D. 52,647, filed September 15, 1958 for a design for a Floral Marker.

The dominant features of my design reside in the full line portions of the drawing.

I claim:

The ornamental design for a floral memorial marker, substantially as shown and described.
